CLAIM

The ornamental design for an airless tire, as shown and described.

DESCRIPTION

FIG. 1 is a top, front, right-side perspective view showing an embodiment of an airless tire of my design. The top, rear, right-side perspective view of the airless tire can be a mirror image of what is shown in FIG. 1.

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

Any features in broken line form no part of the claimed design.

1 Claim, 5 Drawing Sheets
